UNITED STATES PATENT OFFICE.

NELS H. HASSEL, OF LOS ANGELES, CALIFORNIA.

SHOE.

1,126,458.

Specification of Letters Patent. Patented Jan. 26, 1915.

Application filed June 18, 1914. Serial No. 845,956.

To all whom it may concern:

Be it known that I, NELS H. HASSEL, a citizen of the United States, residing at Los Angeles, in the county of Los Angeles, 5 State of California, have invented a new and useful Shoe, of which the following is a specification.

The invention relates to shoes, and the principal object of the invention is to provide a shoe in which a layer of waterproof material is incorporated in the sole for the purpose of preventing moisture from working up through the sole.

In the drawings which are for illustrative purposes only: Figure 1 is a side elevation of a shoe equipped with the invention. Fig. 2 is a section on the line x^2-x^2 of Fig. 1 looking in the direction of the arrows. Fig. 3 is a plan view of the shoe 20 inverted, showing a section of the sole bent back to show the waterproof material.

In these drawings, 1 is the upper of a shoe having a vamp 2, an upper sole 3, a lower sole 4, and a heel 5. Placed between the soles 3 and 4 is a layer of thin rubber 6 which may be secured in any convenient manner and which prevents moisture from working up through the soles. The layers 3 and 4 are formed of leather and give the 30 wearing qualities necessary in a shoe of this character. The rubber 6 is very thin and is provided simply to give an impervious layer against the action of water. The layer 6 is preferably made of thin rubber or it 35 may be made of oiled linen or other treated fabric or leather. The layer of thin rubber 6 diminishes in thickness toward the outer edge thereof, as indicated at 7, terminating in a knife edge 8, which, when the upper 40 sole 3 and lower sole 4 are stitched, as indicated at 9, is barely discernible on the outer surface of the sole of the shoe without a very close examination. In fact, the shoe when completed has the appearance of 45 any ordinary shoe. By beveling or thinning

the edge of the rubber layer 6, as indicated in the drawings, the shoe, as indicated, has the same appearance as the ordinary shoe, and at the same time the layer of rubber is protected from scuffing and abrasion along 50 the edges thereof.

It will be understood that the edge of the layer of rubber 6 may terminate within the outer edge of the leather soles 3 and 4, in which case such a construction would 55 come within the scope of my invention as herein disclosed. The layer of rubber 6 extends from the toe of the shoe into the heel of the shoe a short distance and terminates as indicated by dotted line 10 in 60 Fig. 3.

My invention, as above described, will be found to be particularly useful for those who do not like the discomfort of wearing rubber overshoes, and is also particularly 65 adapted to be worn during light rains where the wearer of the shoes is not obliged to travel through pools of water, although a shoe constructed as above described will be found even under such circumstances to 70 provide considerable protection.

I claim as my invention:

In a shoe, a sole composed of an upper leather portion, a lower leather portion, a thin layer of rubber secured between said 75 leather portions, said layer of rubber diminishing in thickness toward the edge thereof, and a row of stitching of binding material extending through said upper and lower leather portions and through the diminishing portion of the layer of rubber 80 therebetween adjacent to the edge of said layer of rubber.

In testimony whereof, I have hereunto set my hand at Los Angeles, California, this 85 11th day of June, 1914.

NELS H. HASSEL.

In presence of—

FRED A. MANSFIELD,
FORD W. HARRIS.
